ABSTRACT OF THE DISCLOSURE

A catalytic slurry process for hydrorefining a hydrocarbonaceous charge stock containing hydrocarbon-insoluble asphaltenes. The slurry is a mixture of the charge stock and from about 1.5% to about 25.0% by weight of finely-divided solid particles of nonstoichiometric vanadium sulfide. The process is effected continuously, and preferably in an upflow system wherein the slurry is introduced at a lower portion of a reaction chamber, and the product effluent withdrawn from an upper portion.

APPLICABILITY OF INVENTION

The invention described herein is adaptable to a process for the conversion of asphaltene-containing petroleum crude oil into lower-boiling hydrocarbon products. More specifically, the present invention is directed toward a slurry-type catalytic process for continuously converting atmospheric tower bottoms products, vacuum tower bottoms products (vacuum residuum), crude oil residuum, topped crude oils, coal oil extracts, crude oils extracted from tar sands, etc., all of which are sometimes referred to as "black oils," and which contain a significant quantity of asphaltic material. In particular, the process described herein affords a high degree of asphaltene conversion to hydrocarbon-soluble products, while simultaneously effecting a substantial conversion of sulfurous and nitrogenous compounds to reduce the sulfur and nitrogen concentration of the charge stock.

Petroleum crude oils, particularly the heavy oils extracted from tar sands, topped or reduced crudes, and vacuum residuum, etc., contain high molecular weight sulfurous compounds in exceedingly large quantities. In addition, these black oils contain excessive quantities of nitrogenous compounds, high molecular weight organometallic complexes comprising principally nickel and vanadium, and asphaltic material. Asphaltic material is generally found to be complexed, or linked with sulfur and, to a certain extent, with the organometallic contaminants. Currently, an abundant supply of such hydrocarbonaceous material exists, most of which has a gravity less than 20.0° API at 60° F., a significant quantity having a gravity of less than 10.0° API. This material is generally further characterized by a boiling range indicating that 10% by volume, and generally more, has a normal boiling point above a temperature of about 1050° F.

The process of the present invention is particularly directed toward the catalytic conversion of black oils into distillable hydrocarbons.

Specific examples of the black oils, illustrative of those to which the present invention is especially applicable, include a vacuum tower bottoms product having a gravity of 7.1° API at 60° F., containing 4.05% by weight of sulfur and 23.7% by weight of asphaltenes; and, a vacuum residuum having a gravity of 8.8° API at 60° F., containing 3.0% by weight of sulfur, 4300 ppm. nitrogen and having a 20.0% volumetric distillation temperature of 1055° F. The present invention affords the conversion of the majority of such material, heretofore having been

2

believed virtually impossible. The principal difficulty resides in the lack of a technique which would afford many catalytic composites the necessary degree of sulfur stability, while simultaneously producing lower-boiling products from the hydrocarbon-insoluble asphaltic material. This asphaltic material consists primarily of high molecular weight, nondistillable coke precursors, insoluble in light hydrocarbons such as pentane or heptane.

Heretofore, in the field of catalytic processing of such material, two principal approaches have been advanced liquid-phase hydrogenation and vapor-phase, or mixed phase hydrocracking. In the former type of process, liquid phase oil is passed upwardly, in admixture with hydrogen into a fixed-fluidized catalyst bed. Although perhaps effective in converting at least a portion of the oil-soluble organo-metallic complexes, this type process is relatively ineffective with respect to asphaltics which are dispersed within the charge, with the consequence that the probability of effecting simultaneous contact between the catalyst particles, the hydrogen necessary for saturation and the prevention of coke formation, and the asphaltic molecule is at best remote. The retention of unconverted asphaltics, suspended in a free liquid phase oil for an extended period of time, results in additional flocculation and agglomeration. Some processes have been described which rely primarily upon cracking in the presence of hydrogen and a fixed-bed of a particulate solid catalyst. The latter rapidly succumbs to deactivation as a result of the deposition of coke and metallic contaminants thereon. This type process requires an attendant high-capacity regeneration system in order to implement the process on a continuous basis. Briefly, the present invention involves a method whereby the asphaltic material and catalyst are maintained in a dispersed state within a principally liquid phase rich in hydrogen. The asphaltic material is capable of intimate contact with the catalyst thereby effecting reaction between the hydrogen and asphaltic material; the liquid phase is itself dispersed in a hydrogen-rich gas phase so that the dissolved hydrogen is continuously replenished.

In addition to asphaltenes, sulfurous and nitrogenous compounds, crude oils contain greater quantities of metallic contaminants than are generally found in lighter hydrocarbon fractions such as gasoline, kerosene, light gas oil, etc. A reduction in the concentration of the organometallic contaminants, such as metal porphyrins, is not easily achieved, and to the extent that the same no longer exert a detrimental effect with respect to further processing. When a hydrocarbon charge stock containing metals is subjected to a catalytic cracking process for the purpose of producing lower-boiling compounds, metals become deposited upon the catalyst employed, steadily increasing in quantity until such time as the composition of the catalytic composite is changed to the extent that undesirable results are obtained.

The principal object of the present invention is to provide a much more efficient process for hydrorefining heavier hydrocarbonaceous material, containing insoluble asphaltenes, utilizing a solid, unsupported catalyst. The term "hydrorefining" as employed herein, connotes the catalytic treatment, in an atmosphere of hydrogen, of a hydrocarbon fraction or distillate for the purpose of eliminating and/or reducing the concentration of the various contaminating influences previously described, accompanied by hydrogenation. As hereinabove set forth, metals are generally removed from the charge stock by deposition of the same onto the catalyst employed. This increases the amount of catalyst, actively shields the catalytically active surfaces and centers from the material being processed, and thereby generally precludes the efficient utilization of a fixed-bed catalyst system for processing such contaminated crude oil. The present invention

solves the use of a colloidally dispersed, unsupported catalytic material in a slurry process. The present process yields greater yields of a liquid hydrocarbon product which is more suitable for further processing without encountering the difficulties otherwise resulting from the presence of the foregoing contaminants.

OBJECTS AND EMBODIMENTS

As hereinbefore set forth, a principal object of the present invention resides in providing a process for hydrorefining petroleum black oils. A corollary object is to convert hydrocarbon-insoluble asphaltenes into hydrocarbonable, lower-boiling normally liquid products.

Another object is to effect removal of sulfurous and oxygenous compounds by conversion thereof into hydrocarbons, hydrogen sulfide and ammonia.

A specific object is to effect the continuous decontamination of asphaltene black oils by providing a slurry process utilizing a solid, unsupported catalyst.

Another specific object is to provide a novel composition of non-stoichiometric vanadium sulfide in which the molar ratio of sulfur to vanadium is in the range of from 1 to about 1.8:1.

Therefore, in one embodiment, our invention encompasses a process for hydrorefining a hydrocarbonaceous charge stock, containing hydrocarbon-insoluble asphaltenes, which process comprises reacting said charge stock with hydrogen, and in admixture with a vanadium sulfide, in a hydrorefining reaction zone at hydrorefining conditions selected to convert insoluble asphaltenes into lower-boiling soluble hydrocarbons.

A more specific embodiment of our invention involves a slurry process for hydrorefining an insoluble asphaltene-containing hydrocarbonaceous charge stock which comprises reacting a colloidal mixture of said charge stock from about 1.5% to about 25.0% by weight of non-stoichiometric vanadium sulfide, having a sulfur to vanadium atomic ratio of from 0.8:1 to about 1.8:1, with hydrogen in a reaction zone at hydrorefining conditions including a reaction zone inlet temperature of from about 250° C. to about 380° C., and a pressure within the range from 1500 to about 4000 p.s.i.g., and recovering a normally liquid product effluent of decreased asphaltene concentration.

Other embodiments of our invention reside in the utilization of particular operating conditions and techniques; etc., as well as other objects and embodiments will be apparent from the following detailed summary of invention.

SUMMARY OF INVENTION

The unsupported catalyst, utilized in the slurry process of the present invention, is a vanadium sulfide of non-stoichiometric sulfur content. Through the use of the term "unsupported," it is intended to designate a catalyst, or catalytic component, which is not an integral part of a composite with a refractory inorganic oxide carrier material. That is, the catalyst is a vanadium sulfide without addition thereto of extraneous material. While the molar atomic ratio of sulfur to vanadium is not known with accuracy, we have found that the catalytic vanadium sulfide, which is herein referred to as VS_x , has a ratio of sulfur to vanadium not less than 0.8:1, nor greater than 1—e.g., the numerical value of "x" in the foregoing empirical formula lies in the range of 0.8 to 1.8. Furthermore, this is not intended to mean that the vanadium sulfide catalyst has but a single specific sulfur/vanadium ratio, but rather connotes a mixture of vanadium sulfides having sulfur/vanadium mole ratios in the aforesaid range. While four oxidation states are known for vanadium, i.e., 4 and 5, Periodic Chart of The Elements, E. H. Gossen & Company, 1964, only three stoichiometric vanadium sulfides are sufficiently stable for identification. These are: monovanadium sulfide, VS ; sesquivanadium sulfide, V_2S_3 ; and pentavanadium sulfide, V_2S_5 , Handbook

of Chemistry and Physics, Chemical Rubber Publishing Company, 42nd ed., page 680, 1960-1961. Many non-stoichiometric vanadium sulfides have been identified in the literature, including, and possibly the most common, VS_4 , commonly referred to as the tetrasulfide. Significantly, the vanadium sulfide we have found is not identifiable as any of the stoichiometric vanadium sulfides, or as VS_4 .

The principal utility of the nonstoichiometric VS_x resides in the conversion of hydrocarbonaceous material. While, as hereinbefore stated, and as hereinafter set forth in specific examples, the use of our nonstoichiometric vanadium sulfide in the conversion of asphaltic, high metals-containing hydrocarbon charge stock affords unusual advantages, it may be utilized in other hydrocarbon conversion processes which lend themselves to slurry-type processing. Such processes include dehydrogenation of paraffinic hydrocarbons, catalytic reforming of naphtha boiling range charge stocks, dehydrogenation of alkyl aromatics, cracking of polynuclear concentrates such as light cycle stocks, the dealkylation of alkylaromatic hydrocarbons, etc.

In the preparation of nonstoichiometric VS_x of the present invention, we have found it convenient to initially prepare the nonstoichiometric VS_4 , vanadium tetrasulfide. Upon reduction in an atmosphere of hydrogen, the VS_4 is converted to the VS_x , where "x" ranges from 0.8 to 1.8 as hereinbefore set forth. The vanadium tetrasulfide is prepared by reducing vanadium pentoxide with sulfur dioxide and water to yield solid vanadyl sulfate trihydrate. The latter is treated with hydrogen sulfide at a temperature in the range of 250° C. to about 350° C.—i.e., 300° C.—to form the vanadium tetrasulfide. The vanadium tetrasulfide is subsequently reduced in hydrogen at a temperature above about 300° C. to produce the catalytic VS_x having the aforesaid sulfur/vanadium atomic ratios. Since substantially complete reduction of VS_4 to VS_x is desired, and the catalytic action of the latter within the slurry with the charge stock is enhanced when existing in finely-divided form, it is preferable to grind the vanadium tetrasulfide to about 100/200 mesh prior to reducing the same with hydrogen.

In view of the fact that the charge stock is reacted with hydrogen, being admixed therewith in an amount greater than 10,000 s.c.f./bbl., the reduction of the vanadium tetrasulfide is facilitated when it is slurried with the charge stock and hydrogen. Upon being heated to the desired reaction zone inlet temperature, prior to being introduced thereto, the tetrasulfide is reduced to the catalytic VS_x with the sulfur/vanadium mole ratios in the range of 0.8:1 to about 1.8:1. While the tetrasulfide can be reduced to VS_x prior to forming the colloidal slurry, the foregoing procedure is preferred since a savings in hydrogen is realized, and one step of the overall scheme is eliminated. In either event, it is understood that the catalytic vanadium sulfide is the reduced tetrasulfide, and not the latter prior to reduction. Furthermore, since VS_4 is unstable above a temperature of 300° C., the reduction thereof with the hydrogen admixed with the charge stock is facilitated as the reaction zone inlet temperature of 325° C. to about 380° C. is attained.

The concentration of VS_x within the charge stock is at least 1.5% by weight thereof, calculated on the basis of elemental vanadium. Excessive concentrations do not appear to enhance the results, even with extremely contaminated stocks with very high asphaltene content. Therefore, the upper limit of the vanadium sulfide is about 25.0% by weight. The colloidal slurry is admixed with hydrogen in an amount of from 10,000 to 100,000 s.c.f./bbl. of charge stock. Following suitable heat-exchange with various hot effluent streams, the temperature of the mixture is further increased to the level desired at the inlet to the reaction zone. Since the reactions being effected are principally exothermic, the

temperature of the effluent from the reaction zone will be considered higher than the inlet temperature. Therefore, the inlet temperature will be controlled in the range of from 325° C. to about 380° C. The residence time in the reaction zone is such that the effluent temperature is not higher than about 500° C. We have found that excellent results are attainable when the temperature gradient is 380° C. to about 450° C. The reaction zone is maintained under an imposed pressure greater than about 1000 p.s.i.g., and preferably at a level of from 1500 to about 4000 p.s.i.g.

Although the present process may be effected in an elongated reaction zone with the slurry and hydrogen being introduced into the upper portion thereof, the effluent being removed from a lower portion, an upflow system offers numerous advantages. A principal advantage resides in the fact that the extremely heavy portion of the charge stock has an appreciably longer residence time within the reaction zone, with the result that a greater degree of conversion is attainable, and incoming hydrogen will effectively strip lower boiling products therefrom. Also, the heavy, unconverted asphaltic material can be withdrawn from the bottom of the reaction zone along with solid particles of vanadium sulfide. The liquid product effluent, containing distillable hydrocarbons, along with hydrogen, hydrogen sulfide, ammonia and a minor quantity of normally gaseous hydrocarbons, principally methane, ethane and propane, are removed from the top of the reaction zone. A hot flash system, functioning at essentially the same pressure as the reaction zone in a first stage, and at a substantially reduced pressure in a second stage, serves to separate the overhead product effluent into a vapor phase, the principal portion of which boils below about 800° F. and a liquid phase boiling above about 800° F. The latter may be recycled to combine with the fresh charge stock, thereby serving as a diluent, or it may conveniently be employed to facilitate the introduction of fresh and/or regenerated catalyst to the reaction zone in admixture with the charge stock.

The principally vaporous phase passes into a cold high pressure separator (about 60° F. to 120° F.), wherein a hydrogen-rich gaseous phase is recovered and recycled, along with make-up hydrogen to supplant that consumed within the reaction zone. The normally liquid phase from the cold separator, containing some butanes, is generally subjected to fractionation to prepare a charge stock suitable for further processing.

With respect to the bottoms stream from the hot flash system, while this may be totally recycled to combine with the fresh hydrocarbonaceous charge, it is a preferred operating technique to withdraw a drag stream containing at least about 10.0% by weight of the catalyst employed. Any suitable means may be utilized to separate the solid catalyst from the liquid phase hydrocarbons, including filtration, settling tanks, a series of centrifuges, etc. A like quantity of fresh, or regenerated catalyst is then added in order to maintain the selected catalyst content of the slurry.

The catalyst withdrawn with the drag stream is separated, for example, by a series of filtration and methyl naphthalene washing techniques. Methyl naphthalene is employed to remove residual, soluble hydrocarbons from the catalyst sludge. Other suitable solvents include n-heptane, benzene, toluene, etc. The remainder of the catalyst sludge is burned in air to produce vanadium pentoxide which is reduced with sulfur dioxide and water to produce vanadyl sulfate. The regeneration procedure then follows the previously described preferred scheme for the preparation of fresh vanadium sulfide.

The following examples are introduced for the primary purpose of further illustrating the slurry process of the present invention, and to indicate the benefits afforded through the use thereof in the hydrorefining of asphaltene-containing black oils.

EXAMPLE I

A Boscan crude oil was processed continuously in an upflow operation with a suspended vanadium catalyst. The pertinent charge stock properties are given in the following Table I:

Table I.—Boscan crude oil properties

°API at 60° F.	8
Molecular weight	61
Heptane-insolubles, wt. percent	16
Sulfur, wt. percent	6
Nitrogen, p.p.m.	651
Total metals, p.p.m.	141

A vacuum Engler Distillation indicated an initial boiling point of 535° F., a 30.0% by volume distillation temperature of 910° F., with 41.0% being distillable about 1050° F.

Previous work with a batch process had proved successful where the catalyst was prepared in situ from an organovanadium compound. For the instant operation, the catalyst was produced in the reaction zone by decomposing vanadyl acetylacetone, dissolved in methyl naphthalene, under a pressure of 3000 p.s.i.g. (hydrogen-hydrogen sulfide (10.0% hydrogen sulfide). The Boscan crude oil was processed at a temperature gradient of 370° C. to 425° C. and a charge rate of 75 grams per hour. Hydrogen circulation was in the amount of about 2.5 s.c.f./hr. At these conditions, heptane-insoluble conversion was about 90.0%, as was the metallic contaminant removal. Approximately 50.0% of the nitrogen and 60.0% of sulfur was removed, and the gravity increased to 20.6° API. At the termination of this operation, an inspection of the reaction zone internals indicated a deposit of approximately $\frac{1}{8}$ -inch thickness on the wall. Analysis of this material further indicated that it contained about 12.0% by weight of unconverted asphaltene the remainder being principally vanadium and sulfur.

Although the degree of contaminant removal was encouraging during the initial phase of the operation, the efficiency began declining, ostensibly due to the accumulation of vanadium sulfide, having a sulfur to vanadium ratio of about 2.0:1, on the interior walls of the reactive vessel.

EXAMPLE II

The procedure followed in the foregoing Example was repeated with one exception: the quantity of catalyst (as vanadium) was increased about 50.0%. Asphaltene conversion was 83.0%, and 86.0% of the metals, 72.0% of sulfur and about 55.0% of nitrogen was removed. The apparent reason for no increase in conversion, or contaminant removal, at the higher catalyst concentration was attributed to the deposition, once again, of vanadium sulfide and coke onto the walls of the reaction vessel. Seemingly, increasing the catalyst concentration serve only to increase the measurable thickness of the deposit.

EXAMPLE III

Boscan crude oil was again processed in upflow fashion charging 75 grams/hr. at a temperature gradient of 370° C. to 440° C. The pressure was 3000 p.s.i.g. and the hydrogen recycle rate was 14 s.c.f./hr. (15,000 s.c.f./bbl. of crude). In this particular instance, the reaction vessel was ceramic-lined with a titanium-based porcelain enamel in an attempt to obtain a reduction in the amount of deposit upon the interior walls.

Initial results were improved considerably: 97.0% of the asphaltenes were converted, 98.0% of the metallic contaminants, 72.0% of the sulfur and 58.0% of the nitrogen. However, after 28 hours of operation, a pressure drop across the reactor developed. Following an additional 30 hours, a pressure differential of about 25 p.s.i.g. necessitated a cessation of the operation. Again, an inspection of the reactor internals revealed a heavy de-

t on the walls as well as the screen placed near the of the vessel.

EXAMPLE IV

or this series of operations, an aqueous solution of vanadyl sulfate was charged to the reaction zone in admixture with the crude oil charge stock. The vanadylate solution had a specific gravity of 1.0528 at 60° F., contained 1.66% by weight of vanadium. Operating dilutions, at the outset, included a temperature gradient of 75° C. to 420° C., a pressure of 3000 p.s.i.g., a hydrogen recycle rate of 84 s.c.f./hr. (90,000 s.c.f./bbl.), a charge rate of 150 grams/hr. and a catalyst solution rate of 50 cc./hr. After 22 hours of operation, about 15% of the heptane-insolubles and 87.0% of the metals were converted. The gravity of the normally liquid product effluent had increased to 15.0° API from the 8.1° of the fresh charge stock.

At about 35 hours on-stream, a noticeable pressure drop was experienced across the reaction zone, and the production of charge stock and catalyst solution was disrupted. After three hours of hydrogen circulation, charge was reintroduced at a rate of 75 grams/hr. and the temperature gradient increased to 360° C. to 420° C. At the termination of 167 on-stream hours, analyses of the normally liquid product effluent indicated the results presented in the following Table II:

Table II.—Product analyses

Specific gravity, °API	21.5
Heptane-insolubles, wt. percent	0.21
Sulfur, wt. percent	2.12
Hydrogen, p.p.m.	3720
Metals, p.p.m.	9
Heptane-solubles, vol. percent	97.5

During the next 24 hours, the charge stock was changed to vacuum tower bottoms product having the properties indicated in the following Table III:

Table III.—Vacuum tower bottoms properties

Specific gravity, °API	9.8
Heptane-solubles, vol. percent at 1050° F.	30.0
Heptane-insolubles, wt. percent	5.2
Sulfur, wt. percent	3.06
Hydrogen, p.p.m.	4030
Metals, p.p.m.	98

At the termination of 191 on-stream hours, analyses of the normally liquid product effluent indicated the results presented in the following Table IV:

Table IV

Specific gravity, °API	19.6
Heptane-insolubles, wt. percent	0.14
Sulfur, wt. percent	1.17
Hydrogen, p.p.m.	3000
Metals, p.p.m.	9
Heptane-solubles, vol. percent	90.5

The charge stock and catalyst solution introduction ceased, but hydrogen circulation continued for an additional period of about 42 hours. Heaters and hydrogen compressor were shut off, and depressuring was begun. The reaction zone would not depressurize completely. Toluene was charged at a rate of 200 cc./hr. at a temperature of 150° C.; this was followed, after 2 hours, by methyl naphthalene for 18 hours at 200° C. Toluene was injected for an additional six hours at a temperature of 75° C. This procedure permitted the complete depressurizing of the reaction zone which upon being opened, was found to be completely packed with solid material removable only by drilling. The recovered material was treated with methyl naphthalene, to remove organic soluble material, and subsequently with pyridine. The individual washings were precipitated with pyridine, the pyridine-washed precipitate being recovered in an amount of about 95 grams. The solids contained no sulfur, but 8.1% by weight of nitrogen and about 5.0% by weight of vanadium.

The plugging of the reaction zone, evidenced by the pressure differential, is attributable primarily to the accumulation of unconverted heptane-insoluble asphaltenes in the zone. This apparently arises as a result of the phase separation which occurs during the decomposition of the vanadyl sulfate in the presence of the asphalts. This appears to create an environment conducive to the formation of asphaltic complexes at the reaction conditions employed.

EXAMPLE V

The charge stock utilized in this example was the previously described vacuum tower bottoms. Vanadium pentoxide was reduced in sulfur dioxide and water to prepare vanadyl sulfate trihydrate. The latter was treated in a hydrogen sulfide atmosphere at 300° C. and the resulting vanadium tetrasulfide was ground to about 100/200 mesh. 832 grams of the tetrasulfide was added to 1200 grams of the vacuum tower bottoms in a colloid mill over a period of about four hours. The reaction zone was preloaded with about 255 grams of the oil-vanadium tetrasulfide mixture, and the unit was pressurized to about 3000 p.s.i.g. A hydrogen recycle rate of 14 s.c.f./hr. (about 30,000 s.c.f./bbl.) was established.

The block-heater temperature was raised to 100° C., and held for one hour, after which the block-heater temperature was raised to 300° C. At this point the vacuum tower bottoms, with the vanadium tetrasulfide, was introduced into the heater, in admixture with the circulating hydrogen stream. The temperature gradient, as measured from the reaction zone inlet, to the outlet was controlled at about 320° C. to 385° C., by controlling the furnace (block-heater) skin temperature at about 410° C. The charge rate was 75 ml./hr. and makeup hydrogen in an amount of about 4.75 s.c.f./hr. was added to the process.

Greater than 99.0% heptane-insoluble conversion was attained, and the operation was terminated at 116 on-stream hours voluntarily, without experiencing noticeable pressure drop across the reactor. After charging 1200 grams of the vacuum tower bottoms, analyses indicated about 0.03% by weight of asphaltenes in the product effluent, less than 5 p.p.m. of vanadium complexes (as elemental vanadium) and about 6 p.p.m. of nickel. The gravity of the normally liquid product had increased to 16.5. A material balance, with respect to the vanadium introduced as catalyst, indicated very little loss by way of deposit on the walls of the vessel.

The foregoing specification clearly indicates the method by which the present invention is effected. Data presented illustrates the benefits and advantages resulting from the use of our invention in a process for hydrorefining asphaltene-containing hydrocarbonaceous black oils.

We claim as our invention:

1. A process for hydrorefining a hydrocarbonaceous charge stock, containing hydrocarbon-insoluble asphaltenes, which process comprises reacting said charge stock with hydrogen, and in colloidal admixture with non-stoichiometric vanadium sulfide, having a sulfur to vanadium atomic ratio of from 0.8:1 to about 1.8:1 and excluding VS and V₂S₃, in a reaction zone at hydrorefining conditions selected to convert insoluble asphaltenes to lower-boiling soluble hydrocarbons.

2. The process of claim 1 further characterized in that said hydrorefining conditions includes a temperature of from about 325° C. to about 500° C. and a pressure greater than about 1000 p.s.i.g.

3. The process of claim 1 further characterized in that said charge stock is admixed with vanadium sulfide in an amount of at least 1.5% by weight, as elemental vanadium.

4. The process of claim 1 further characterized in that hydrogen is present in said reaction zone in an amount of at least about 10,000 s.c.f./bbl. of said charge stock.

5. A slurry process for hydrorefining an insoluble asphaltene-containing hydrocarbonaceous charge stock which comprises reacting a colloidal admixture of said charge stock and from about 1.5% to about 25.0% by weight of nonstoichiometric vanadium sulfide, having a sulfur to vanadium atomic ratio of from 0.8:1 to about 1.8:1 and excluding VS and V_2S_3 , with hydrogen in a reaction zone at hydrorefining conditions including a pressure of from 1500 to 4000 p.s.i.g. and a reaction zone inlet temperature of from 325° C. to about 380° C.,

and recovering a normally liquid product effluent of decreased asphaltene concentration.
